UNITED STATES PATENT OFFICE

168,159

REFRIGERATOR CABINET

Theodore H. Koeber, Oak Park, Ill., Benton Dales, Evansville, Ind., and Dave Chapman, Chicago, Ill., assignors to International Harvester Company, a corporation of New Jersey

Application July 15, 1952, Serial No. 20,613

Term of patent 7 years

(Cl. D67—3)

To all whom it may concern:

Be it known that we, Theodore H. Koeber, Benton Dales, and Dave Chapman, citizens of the United States, residing, respectively, at Oak Park, in the county of Cook, State of Illinois, and Evansville, in the county of Vandenburgh, State of Indiana, and Chicago, in the county of Cook, State of Illinois, have invented a new, original, and ornamental Design for Refrigerator Cabinet, of which the following is a specification, reference being had to the accompanying drawings, forming part thereof, in which:

Fig. 1 is a perspective view taken from one side of a refrigerator, showing our new design.

Fig. 2 is a perspective view taken from the other side thereof.

Fig. 3 is a horizontal sectional view of the cabinet door taken on line 3—3 of Fig. 1 and illustrates in detail the depressed portions.

Fig. 4 is a horizontal sectional view similar to Fig. 3 but taken on line 4—4 of Fig. 1.

Fig. 5 is a horizontal sectional view similar to Figs. 3 and 4 but taken on line 5—5 of Fig. 1.

Fig. 6 is a vertical sectional view taken on the line 6—6 of Fig. 2.

Fig. 7 is a vertical sectional view taken on line 7—7 of Fig. 2; and

Fig. 8 is a vertical sectional view taken on line 8—8 of Fig. 2.

The dominant features of our design reside in the portions shown in full lines.

We claim:

The ornamental design for a refrigerator cabinet, substantially as shown and described.

THEODORE H. KOEBER.

BENTON DALES.

DAVE CHAPMAN.
